UNITED STATES PATENT OFFICE.

WILLIAM F. KIESEL, JR., OF ALTOONA, PENNSYLVANIA.

DRIFTING VALVE.

Application filed January 17, 1920. Serial No. 352,002.

To all whom it may concern:

Be it known that I, WILLIAM F. KIESEL, Jr., a citizen of the United States, and residing at Altoona, Blair County, State of Pennsylvania, have invented certain new and useful Improvements in Drifting Valves, of which the following is a specification.

The present invention relates to drifting valves for locomotives, and more particularly to the type which is adapted to supply live steam to the cylinders, superheater or valve chests.

Various forms of drifting valves have been devised, but most of them require very little difference in pressure to open or close the same. Because of the slight difference in pressure required for opening and closing, such valves flutter considerably, and consequently it is practically impossible to prevent creating a long period of vacuum in the valve chamber. The principal object of the present invention is to provide a valve which will open certainly, and when a slight vacuum is created in the valve chamber. A further object is to provide a valve which will not close unless there is an appreciable positive pressure in the valve chambers.

To these ends the present valve includes a sleeve which is provided with an auxiliary surface on which the steam pressure acts to hold the valve open until the pressure in the steam chest reaches a point considerably above the pressure at which the valve opened.

Other objects and features of novelty of the invention will be apparent from the description taken in connection with the drawings, in which—

Fig. 1 is a sectional elevation of a valve constructed in accordance with the present invention, the valve being shown in closed position;

Fig. 2 is a sectional elevation of the valve shown in Figure 1 illustrating the valve in open position;

Fig. 3 is a sectional elevation showing a valve similar to that illustrated in Figure 1. In this case however the weight of the sleeve tends to close the valve, rather than open it.

The valve in this figure is shown closed;

Fig. 4 shows the valve of Figure 3 in open position;

Fig. 5 illustrates a modified form of the invention, the valve being shown in closed position;

Fig. 6 shows the valve of Figure 5 in open position; and

Fig. 7 is a top plan view of the valve shown in Figures 5 and 6, certain parts being shown in section, the section being taken on the line 7—7 of Figure 6.

Referring to the valve shown in Figures 1 and 2, the numeral 10 indicates a valve body having two interior cylindrical surfaces 11 and 12, the latter being of larger diameter than the former. The valve body 10 is closed at one end by a head 13, but passages 14 disposed adjacent the head, place the interior of this end of the body in communication with the atmosphere. The opposite end of the valve body has a head 15 secured thereto, as by bolts 16, this head having communication through the pipe 17 with a steam chest of a cylinder of a locomotive, or with a superheater or other part at substantially the same pressure as the valve chest. The head 15 is disposed so as to form a shoulder 18 at the end of the large cylindrical portion 12 of the body for a purpose presently to be described. A boss 19 on one side of the valve body receives the pipe 20 leading from the boiler, and this pipe is in communication with the annular passage 21 extending around the valve body. The inner end of the valve body is in communication with this annular passage through the ports 22 extending through the wall of the valve body.

Slidably mounted in the cylindrical portions of the valve body is a differential sleeve 23 having a portion 24 slideable in the cylinder 11 and a larger portion 25 rigidly connected thereto slideable in the cylinder 12. The end of the small portion of the sleeve is closed by a head 26, whereas the opposite end of the sleeve is open and in communication with the pipe 17 leading to the superheater or valve chest. Intermediate its ends the small portion of the sleeve is provided with a series of ports 27 extending through its wall which are adapted to register with the ports 22 of the valve body when the valve is opened. Suitable reinforcing ribs on the interior of the sleeve are provided to compensate for the metal omitted due to the ports 27. Adjacent the point where the small and large portions of the sleeve are joined together, the small portion on its interior is provided with an inwardly extending annular wall 28. As shown, this wall is frus-

tra-conical and projects towards the closed end of the sleeve. It is formed with the centrally disposed aperture 29, which is of smaller diameter than the pipe 17 leading to the steam chest. Adjacent the point where the wall 28 joins the sleeve, are a series of ports 30 provided for a purpose presently to be described.

The valve is intended to be disposed vertically, as shown in Figures 1 and 2, being shown in closed position in Figure 1 and open in Figure 2. When the throttle valve controlling the supply of steam to the steam cylinder is closed and the locomotive continues in motion, the movement of the pistons in the engine cylinders reduces the pressure in the steam chest and superheater, if one is provided, and further tends to draw in exhaust gases and cinders from the smoke box through the cylinder exhaust passages. The present invention prevents this reduction in pressure. As soon as the pressure in the steam chest or superheater falls below the atmosphere by the slightest amount, the pressure within the sleeve of the drift valve will also be reduced so that the air pressure acting on the closed end 25 of the sleeve moves the sleeve from the position shown in Figure 1 to that shown in Figure 2, bringing the ports 26 of the small portion of the sleeve in register with the ports 22 in the valve body. Steam from the boiler supply through the pipe 20 will thus flow into the interior of the sleeve, thence downward through the ports 30 into the space 31 and act on the differential portion 32 of the sleeve. This, of course, will tend to hold the valve open. The steam also flows through the opening 29 in the wall 28, and thence through the pipe 17 to the superheater or steam chest, thus building up a positive pressure and offsetting any tendency to the production of a vacuum in the engine cylinders.

Due to the fact that the opening 29 in the interior of the sleeve is smaller than the size of the pipe 17, the pressure of the steam in the chamber 33 will be less than the pressure within the small portion of the sleeve. Consequently there is a greater total pressure to keep the valve open than to close it, and this unbalanced pressure will not be overcome until a sufficient pressure has been built up in the steam chest, so that it may be communicated through the pipe 17 to act against the under side of the lower end of the valve sleeve. It will be seen, therefore, that although the present valve opens very quickly and in response to the slightest reduction of the steam chest pressure below atmosphere, it will not close until a substantial pressure above atmosphere has been built up in the steam chest or superheater. The smaller the opening 29, the greater the pressure required before the valve closes.

Hence by properly designing the size of opening 29 and the diameter of pipe 17, the valve may be built to close at any predetermined pressure above atmosphere. It will be observed that the shoulder 18 on the lower head acts to limit the motion of the sleeve in one direction.

With the sleeve of the valve disposed as shown in Figures 1 and 2, the weight of the sleeve tends to open the valve. In order to offset this tendency and have a valve sleeve which is exactly balanced, the interior of the cylinder 10 adjacent the ports 22 is enlarged slightly, as shown at 34, and the sleeve portion 23 is provided with one or more spring rings 35 disposed above the ports 22 when the valve is closed. With this construction it will be seen that the steam entering through the ports 22 acts on the rings 35, thereby tending to hold the sleeve at its upper position. The area of the ring subjected to the steam pressure is such as to just offset the weight of the valve sleeve when the valve is closed. On the other hand when the valve is open, as shown in Figure 2, this steam pressure acting on the ring 35 tends to hold the valve open. Although the force exerted on this ring is relatively small, yet it adds to the total required to be overcome in order to close the valve.

In Figures 3 and 4 a valve similar to that shown in Figures 1 and 2 is illustrated, but in an inverted position. The only difference is that the enlarged bore 34 of Figures 1 and 2 is not provided, this not being necessary for the reason that the weight of the sleeve of the valve of Figures 3 and 4 tends to close the valve. The parts shown in Figures 3 and 4 corresponding to those shown in Figures 1 and 2 are indicated by the same reference numerals primed. This valve operates the same as that described in connection with Figures 1 and 2, except that the weight of the sleeve must be overcome before the valve is opened. For this reason the form shown in Figures 3 and 4 is a little less sensitive in opening than that shown in Figures 1 and 2.

In the form of the invention illustrated in Figures 5 and 6, the valve body 110 has two cylindrical portions 111 and 112, the latter being of the smaller diameter. The cylindrical part 112 is closed at one end by a head 113, having a port 114 providing communication between the space at the interior of the head and the atmosphere. The opposite end of the body 110 is closed by a head 115 provided with a passage 133, which leads to a pipe 117 adapted to extend to the steam chest, superheater or other part connected with the cylinders of the engine. A passage 121 is formed in the body 110 and is in communication with the interior of the cylinder 111 and also has connection 130

with the boiler through the pipe 120 screwed into the boss 119.

Disposed within the cylinders 111 and 112 is a differential sleeve valve comprising the small cylindrical part 123 and the larger cylindrical part 124. The end of the sleeve 123 adjacent the head 113 is closed by a wall 125, the opposite end of the sleeve 124 being opened and in communication with the steam chest or other similar part. Adjacent the differential surface 132 of the sleeve, one of the sleeve portions, as the smaller, is provided with a series of ports 126 extending through its wall, suitable reinforcing ribs 127 being provided to compensate for the loss of strength due to these ports.

In the operation of this form of the invention, the slightest reduction below atmospheric pressure in the steam chest or superheater will produce a corresponding reduction of pressure within the sleeve of the valve so that the air pressure acting on the head 125, will move the sleeve upward until its upper end strikes the shoulder 118. This movement opens the valve placing the ports 126 in communication with the passage 121, so that steam is supplied to the interior of the valve and thence through the pipe 117 to the steam chest. Furthermore the steam pressure acts on the differential surface 126 to hold the valve open until such time as a pressure sufficient to overcome the opening force is built up in the steam chest and the interior of the valve sleeve.

Although several forms of the invention have been described in detail, it is to be understood that the invention is not thus limited, but includes modifications and changes which come within the scope of the appended claims.

Having thus described the invention what is claimed as new and desired to be secured by Letters Patent is:

1. An automatic drifting valve comprising in combination, a valve body, a differential sleeve slidable therein adapted to control the supply of steam from the boiler to the steam chest, said sleeve being closed at its small end and open at its other, the space in the valve body at the small end of the sleeve being in communication with the atmosphere and the opposite end in communication with the steam chest, ports in the body and sleeve adapted to be placed in communication when the sleeve is moved in one direction because of the reduced pressure in the steam chest, the ports in the body being adapted for connection to the boiler whereby steam under pressure is supplied to the steam chest, and means for conducting steam to act on the differential area of said sleeve when the said ports are open, whereby the valve is held open until a substantial pressure has been built up in the steam chest.

2. A drifting valve comprising in combination, a body having two cylindrical portions of different interior diameters, the end of the smaller cylindrical portion being in communication with the atmosphere, and the large diameter portion being in communication with the steam chest, a differential sleeve valve having two portions one fitting the small and the other the large cylinder portion, said sleeve closed at its small end and open at its large end, the small cylindrical portion of the body having a port in its wall adapted to be connected with the boiler, said small sleeve portion having ports through its wall adapted to come in communication with the first mentioned port, and to supply steam to the differential area between the two portions of the piston to hold the valve open until a substantial pressure has been built up in the steam chest.

3. A body comprising two cylindrical portions of different diameters, the small end being in communication with the atmosphere and the other end adapted to be placed in communication with part of the locomotive substantially at same pressure as in the steam chest, said body having a port through its wall adapted to be connected to a supply of steam, a sleeve member comprising parts of different diameters rigidly connected and slidable in said cylindrical portions, one part in each cylindrical portion, the end of the small sleeve being closed, said small sleeve having an aperture through its wall adapted to admit steam from said port to the interior of the sleeve when it is in one position and means to supply steam to the annular space formed between the wall connecting the small and large sleeve and the corresponding wall of the body when the valve is open to thereby hold it open until there is a substantial pressure in the steam chest.

4. An automatic drifting valve comprising in combination, a differential valve body in communication with the atmosphere at its small end and adapted for connection to the steam chest at its other end, a differential sleeve slidably fitted in the body having its small end closed and its large end formed with a relatively small central aperture, a steam port in the wall of the small diameter portion of the body, a port in the small diameter part of the sleeve adapted to register with the said port in the body when the valve is open, and a second port in the wall of the small part of the sleeve adjacent the large part, said last mentioned port being automatically closed when the valve is closed.

In testimony whereof I affix my signature.

WILLIAM F. KIESEL, JR.
